UNITED STATES PATENT OFFICE.

GEORGE W. BULLEY, OF AKRON, OHIO.

RADIOCABINET.

Original application filed July 30, 1925, Serial No. 47,118. Divided and this application filed November 25, 1925. Serial No. 71,381.

This application is a division of an application filed by me in the United States Patent Office July 30, 1925, Serial No. 47,118.

My present invention relates to improvements in hard rubber containers and aims more particularly to provide a radio cabinet composed entirely of hard vulcanized rubber, and the invention includes the novel article hereinafter described and defined by 10 the appended claim.

In the accompanying drawings:

Figure 1 is a front elevation of the completed article.

Fig. 2 is a transverse vertical section, and

Fig. 3 is a sectional detail on line 3-3 of Fig. 2.

Referring by reference characters to this drawing, the numeral 1 designates the body of the cabinet, which is of approximately 20 rectangular form, having an integral bottom and side and end walls, which are formed of vulcanized hard rubber in a unitary one piece article. Preferably the bottom is provided with a base flange indicated at 1^a and 25 the front wall may have one or more openings formed therein, as indicated at 1^b, which may be used as grid opening for an internal loud speaker.

2 designates the cabinet top, which is provided with depending side walls 2^a integral- 30 ly united to each other at the corners, the top being sufficiently large to enable the walls 2^a to slip down over the walls of the body. The body and top are preferably formed in the manner disclosed in my afore- 35 said application.

In molding the covers it is practically impossible to provide the same with sharp interior corners, such interior corners usually being of approximately the shape shown 40 at 1^a. To enable the cover to be easily applied to the body without unduly enlarging it, I provide the body with reduced or grooved corners, as indicated at 2^a.

Having thus described my invention, what 45 I claim is:

As an article of manufacture, a unitary hard rubber open topped container body having a hard rubber slip cover, the inside of the cover at the meeting edges of the sides 50 having thickened portions and the corners of the receptacle which are in line with the cover when in place being rebated.

In testimony whereof, I affix my signature.

GEORGE W. BULLEY.

Certificate of Correction.

It is hereby certified that Letters Patent No. 1,591,359, granted July 6, 1926, upon the application of George W. Bulley, of Akron, Ohio, for an improvement in "Radiocabinets," were erroneously issued to the inventor, said "Bulley," whereas said Letters Patent should have been issued to *The Miller Rubber Company, of Akron, Ohio, a Corporation of Ohio*, as assignee of the *entire interest* in said Letters Patent, as shown by the records of assignments in this office; and that the said Letters Patent should be read with this correction therein that the same may conform to the record of the case in the Patent Office.

Signed and sealed this 3d day of August, A. D. 1926.

[SEAL.]

M. J. MOORE,
Acting Commissioner of Patents.
